UNITED STATES PATENT OFFICE.

FREDERIC BARNES WALDRON, OF PRESCOT, ENGLAND, ASSIGNOR TO PILKINGTON BROTHERS LIMITED, OF LIVERPOOL, ENGLAND, A BRITISH COMPANY.

APPARATUS FOR POLISHING PLATES OF GLASS, MARBLE, OR OTHER MATERIAL.

Application filed September 5, 1924, Serial No. 735,985, and in Great Britain September 26, 1923.

This invention relates to apparatus for polishing plates of glass, marble or other material, and more particularly to that type of polishing apparatus in which a plurality of polishing blocks, each adapted to rotate about its own axis, are mounted on a framework which rotates about its axis, and said invention has for its object an improved construction of polishing runner whereby the polishing blocks, in normal operation, rotate about their own axes without the need of any means for driving them positively.

According to this invention each polishing block is mounted loosely on its stub spindle, so that it is free to rest evenly on the surface of the glass by its own weight, and the contact between the stub spindle and the block, whereby the latter is held against centrifugal force, is in a plane which passes approximately through the centre of gravity of the block or between the centre of gravity and the operative face of the block.

This invention will be described as applied to the runner commonly employed for polishing glass which consists of a framework mounted on the lower end of a vertical spindle, the said spindle being either positively rotated or free to rotate.

The accompanying drawing is a vertical section through a polishing block, showing a portion of the stub spindle and the mounting of the latter in the framework of the runner.

1 is the runner framework and 2 a stub spindle mounted therein with ball bearings 3. The polishing block 4, covered with a felt 5 is mounted on a boss 6 which is attached to the end of the stub spindle 2 by means of a nut 7. The boss 6 fits loosely in a cylindrical hole in the polishing block 4 and is capable of a small vertical movement therein, which is limited in an upward direction by a plate 8, attached to the block, engaging with a shoulder 9 on the boss 6. By means of the shoulder 9 and plate 8, the block 4 may be lifted clear of the glass by raising the framework of the runner. In operation, the runner framework is lowered so that when the block 4 rests on the glass, the boss 6 is clear of the plate 8 as shown in the drawing.

The periphery 10 of the boss 6, where it contacts with the block 4, is curved, preferably to a portion of a sphere, so that it may contact with the block 4 only along a line

and so that the block 4 may tilt on the boss 6 when required to take an even bearing on the glass.

The line of contact between the boss 6 and the block 4 is in the horizontal plane which is indicated by the dotted line 11 and which passes through the centre of gravity of the block 4 with its felt 5; this plane is, itself, hereinafter identified by the numeral 11.

Now, it is important for effective polishing, that the polishing blocks rotate on their axes and it is found that they do so rotate when they bear on the glass with a pressure which is approximately uniform over their surfaces, or when the pressure at points more distant from the axis of the runner is greater than that at points nearer to it. It appears that the rotation is due to the greater relative velocity between glass and polishing block at points more distant from the axis of the runner and that the effect of the greater relative velocity is annulled by a greater pressure at points nearer to the axis of the runner.

Now, the centrifugal force acting on the block, will produce a couple tending to tilt the block, if the plane in which the block is held against the centrifugal force, be above or below the centre of gravity of the block, and this couple will cause the pressure between glass and block at points more distant from the axis of the runner to be greater if the plane be below, and less if the plane be above, the centre of gravity of the block.

It is an essential feature of this invention that the plane in which the block 6 is held by contact with the periphery 10 of the boss 6, be either substantially in the plane 11 of the centre of gravity of the block or below it, so that the centrifugal force has no appreciable effect in increasing the pressure between glass and block at points nearer to the axis of the runner.

It is to be noted that the polishing block 4 is driven by the boss 6, so that the means for driving the block are the same as the means for holding it against centrifugal force. This is the preferred construction, but the invention is not confined to the particular type of polishing block and mounting shown, and is applicable to any block on a rotating runner, which is free to rotate and to tilt, and is used for polishing or abrading of any description.

Having described my invention, I declare

that what I claim and desire to secure by Letters Patent is:—

1. Abrading apparatus of the type described, comprising abrading blocks free to rotate and tilt, characterized by an abrading block being held against centrifugal force in a plane which is not above the centre of gravity of the block.
2. In abrading apparatus of the type described, the combination with a rotating runner framework and a stub spindle mounted thereon so as to be capable of rotation only,

of a boss attached to the end of the spindle, a polishing block upon the spindle, an opening in the block within which the boss is movable axially, and permitting tilting movement of the block about the boss, the periphery of the boss contacting with the block in a plane which is not above the centre of gravity of the block.

In testimony whereof I have affixed my signature hereto.

FREDERIC BARNES WALDRON.
